This invention relates to a new ornamentation of a carpet, oil-cloth, or similar fabric; and it consists of the novel grouping and out- 15 lines of figures, hereinafter described.

Next to these are rosettes D, placed in a series of horizontal bands, e e, said bands terminating in rosette-shaped points f. Above the field which contains the figures 25 already described is a band, E, containing rosettes g h i and fanciful figures j.
